US00D931900S

(12) **United States Design Patent** (10) Patent No.: **US D931,900 S**
Olety (45) Date of Patent: **** Sep. 28, 2021**

(54) **DISPLAY SCREEN OR PORTION THEREOF WITH GRAPHICAL USER INTERFACE**

(71) Applicant: **Citrix Systems, Inc.**, Fort Lauderdale, FL (US)

(72) Inventor: **Pavithra Rameshbabu Olety**, San Jose, CA (US)

(73) Assignee: **Citrix Systems, Inc.**, Fort Lauderdale, FL (US)

(**) Term: **15 Years**

(21) Appl. No.: **29/724,675**

(22) Filed: **Feb. 18, 2020**

(51) LOC (13) Cl. **14-04**

(52) U.S. Cl.

USPC **D14/492**

(58) **Field of Classification Search**

Primary Examiner — Cary M Robinson

(74) Attorney, Agent, or Firm — Banner & Witcoff, Ltd.

(57) **CLAIM**

The ornamental design for a display screen or portion thereof with graphical user interface, as shown and described.

DESCRIPTION

The FIGURE is a front view of a display screen or portion thereof with graphical user interface showing my new design.

The broken line showing of the text, symbols, display screen, and remainder of the graphical user interface forms no part of the claimed design.

1 Claim, 1 Drawing Sheet
